(57) **CLAIM**

The ornamental design for a shoe organizer, as shown and described.

DESCRIPTION

FIG. 1 is a front perspective view of a shoe organizer, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is the folded state diagram of its top surface;

FIG. 10 is the unfolded state diagram of its top surface;

FIG. 11 is its state diagram;

FIG. 12 is its state diagram;

FIG. 13 is its state diagram;

FIG. 14 is its state diagram;

FIG. 15 is its state diagram; and,

FIG. 16 is an enlarged detail view of area 16 in FIG. 2.

The broken lines in the drawings illustrate the portions of the shoe organizer, which form no part of the claimed design. The dash-dot-dash broken lines encircling the enlarged views are for annotative purposes only and form no part of the claim thereof.
